UNITED STATES PATENT OFFICE.

DAVID E. KERR AND HAROLD WILSON, OF CONNEAUT, OHIO.

CATAPHORIC ELECTRODE.

1,076,210.

Specification of Letters Patent.

Patented Oct. 21, 1913.

Application filed February 26, 1913. Serial No. 750,725.

To all whom it may concern:

Be it known that we, DAVID E. KERR and HAROLD WILSON, both citizens of the United States, residing at Conneaut, in the county 5 of Ashtabula and State of Ohio, have invented certain new and useful Improvements in Cataphoric Electrodes, of which the following is a specification.

This invention relates to electrodes of the 10 class employed to cause electrolyzed substances to enter the human body and the object of our invention is to provide an electrode of this class having a medicine container provided with a part within which the 15 metallic electrode is contained and which can be inserted into a cavity or depression of the body, such as the umbilical depression or navel, and thus more effectively produce the cataphoric or endosmotic action.

20 In carrying out our invention we provide a container for the medicine which is provided with a nipple adapted to enter the depression or cavity and which has a perforation in its outer end through which the 25 medicine passes. Over the nipple we place a cap of gauze, cotton or other such absorbent material and secure this to the nipple by means of a casing which surrounds the container and through which the nipple 30 extends. The container is closed at top by a cover to which is secured a plug carrying a binding post from which a metal electrode depends and which has its lower portion within the nipple. The arrangement is such 35 that the container may be easily opened or closed for filling, cleaning and sealing purposes and for repairs, and when the liquid level has fallen below the lower end of the metallic electrode the electric circuit will 40 be broken.

In the drawings:—Figure 1 is a perspective view of a cataphoric electrode embodying our improvements. Fig. 2 shows a vertical central section thereof with the metallic 45 electrode and binding post in elevation. Fig. 3 is a perspective view of the nipple cap. Fig. 4 is a similar view of the metallic electrode and binding post. Fig. 5 is a perspective view of the casing for the container, 50 and Fig. 6 is a perspective view of the container.

The container A and its casing B are preferably made of hard rubber. The container is formed with a chamber a to receive the 55 medicine and with a nipple a' which com-

municates with said chamber. The nipple has a perforation α in its lower end and is surrounded by a cap D of suitable absorbent material. Preferably the container is of cylindrical form, its bottom sloping toward 60 the nipple, and it is formed with an annular depending threaded flange a^2 and a laterally projecting top flange a^3 . The casing B has an annular flange b threaded to engage the flange a^2 and its bottom b' has a central 65 opening b^2 through which the nipple extends. The flange b is arranged below the flange a^3 and makes a tight fit with it. The container is closed at the top by a cover A' which may if desired be made detachable 70 as shown, and this cover has a central opening to receive a plug E of insulating material which supports the metallic binding post F which carries on its lower end the metallic electrode G. The circuit wire H 75 may be connected with the post by nuts h in the usual way. The plug is detachably connected with the cover and the plug, post and electrode may be readily removed together; when thus removed the medicine may be 80 poured into the medicine receiving chamber.

It will be observed that the cap D is held in place over the nipple by the casing B and that by detaching the casing the cap may be removed and replaced by a fresh one. The 85 medicine passes through the aperture α in the nipple and saturates the cap D and then by reason of its cataphoric properties passes through the cavity of the body into the 90 interior thereof.

Our improved electrode is of simple construction, may be readily assembled or taken apart, may be manufactured cheaply and has been found to be most efficient in operation.

It will be understood that the wire H 95 connects with one pole of a battery the opposite pole of which may be connected with a plate applied, as by means of a belt, to the back of the patient.

We claim as our invention: 100

1. A cataphoric electrode, comprising a medicine container provided with a nipple adapted to enter a cavity or depression of the human body, and a cap of absorbent material covering the nipple. 105

2. A cataphoric electrode, comprising a medicine container provided with a nipple adapted to enter a cavity or depression of the human body, and a casing secured to the container through which the nipple extends. 110

3. A cataphoric electrode, comprising a medicine container provided with a nipple adapted to enter a cavity or depression of the human body, a cover for the container, 5 a plug detachably secured to the cover, and a binding post and metallic electrode carried by the plug.

In testimony whereof, we have hereunto subscribed our names.

DAVID E. KERR.
HAROLD WILSON.
